(57) **CLAIM**

The ornamental design for an arch laminator, as shown and described.

DESCRIPTION

FIG. 1 is a perspective view of the laminator with the dust cover closed.

FIG. 2 is a perspective view of the laminator with the dust cover open.

FIG. 3 is a top elevational view of the laminator with the dust cover closed.

FIG. 4 is a top elevational view of the laminator with the dust cover opened.

FIG. 5 is a front elevational view of the laminator with the dust cover closed.

FIG. 6 is a bottom elevational view of the laminator with the dust cover closed.

FIG. 7 is a bottom plan view of the laminator with the dust cover open.

FIG. 8 is a rear elevational view of the laminator.

FIG. 9 is a left side elevational view of the laminator with the dust cover closed; and,

FIG. 10 is a right side elevational view of the laminator with the dust cover open.

The broken line showing is for illustrative purposes only and forms no part of the claimed design.
